UNITED STATES PATENT OFFICE

LEONARD R. CARLEY, OF WATERTOWN, CONNECTICUT, ASSIGNOR TO PATENT BUTTON COMPANY, OF WATERBURY, CONNECTICUT, A CORPORATION OF CONNECTICUT

FASTENER

Application filed January 16, 1929. Serial No. 332,982.

This invention relates to fasteners of the button type in which the button is secured to fabric or other material by a rivet or tack. The button may be either of the type adapted to cooperate with a loop or the type adapted to cooperate with a mating button of the snap fastener variety. More particularly an object of the invention is to provide an improved fastener construction.

Other objects will be apparent from the following description of a representative embodiment of the invention illustrated in the accompanying drawings wherein:

Figure 1 is a sectional view of the fastener assembly attached to a piece of fabric, the view also showing a setting pin or die employed in attaching the fastener;

Figure 2 is a section of the parts before assembly;

Figure 3 is a view showing the button pierced by a staple and section of the staple-setting die;

Figure 4 is a plan view of a button pierced by a tack showing burrs formed in the piercing operation; and

Figure 5 is an end view of a setting pin for turning the ends of the tack shanks and removing the burrs.

Fasteners of this type are manufactured in great quantities and at a very moderate price, hence there is a constant urge for reduction in the number of parts in the assembly as well as for a simplification of manufacturing methods. At the same time the fasteners must be neat in appearance, substantial in construction, and sanitary and durable in service.

For certain service the simple head of a rivet or tack is of insufficient size and smoothness. It is customary for this service to provide the attaching member such as a rivet or tack with a cap, which cap may be of any required size, may conveniently be made without rough edges and if desired may be embossed with a design. Heretofore a satisfactory and substantial capped rivet or tack of this type has been made of an objectionably great number of parts.

According to this invention the rivet, tack or other attaching member is provided with

a single specially formed and attached cap piece which is sufficiently smooth and substantial to be used alone for many purposes but which may be supplemented by a crown piece where greater strength and neater appearance are desired.

In Figures 1 and 2 the attaching member is seen to be of the headed tack type or more specifically a headed staple comprising pointed prongs 10, a head flange 11 formed integrally with the prongs, and a cap including an attaching disc 12 and if desired a crown disc 20.

The attaching disc 12 is formed with an annular rib 13 (Fig. 2) adapted to be pressed inward (Fig. 1) beneath the head flange of the staple when this flange is positioned within the socket 14 formed by the rib 13. The rib 13 is formed by the merging of the lower edge of a vertical central wall 12' with an upwardly and outwardly sloping wall 13'.

Referring to Figs. 1 and 3, which show the disc 12 now bent to its final form, it will be seen that the vertical wall and sloping wall have been forced inwardly to form a rim 13^a to underlie and hold the staple tightly within the socket 14. The attaching disc 12 is generally convex, the outer portion 15 blending into a common convex surface with the central portion 16 which is somewhat flattened to closely overlie the flanged or head end of the staple. The groove 17 which is formed when the material of the attaching disc is pressed inwardly is quite narrow so there is no considerable separation between the outer and central portions of the disc 12. The rim of the outer portion 15 is adapted to fit closely upon the surface material or goods on which the fastener is used—preferably cooperating with the bottom edge of the attached member to squeeze the goods between them and to this end is located substantially in or slightly below the plane of the bottom surface of the rib 13 when the rib is bent beneath the staple flange, as shown in Fig. 1.

When the crown piece 20, which may be embossed with a design, is used it may be secured to the attaching disc 12 by turning

its outer edge 21 beneath the rim of the disc. The crown closely overlies the disc 12 throughout its extent and the cap assembly thus formed is sufficiently sturdy to withstand driving to pierce a sheet of metal or the action of laundry machinery without being dented or bent.

A piercing staple is more convenient to use in attaching fasteners for the reason that the staple and button may be connected in any relative position if aligned axially and do not need to be in an exact rotated position as is the case where the button is pierced before attachment.

With this piercing staple I employ an imperforate (not apertured for the staple) snap fastener member 30 which is cup-shaped and provided at the bottom of the cupped portion with an annular positioning groove 31 for receiving the points of the staple shanks. The fastener member 30 is formed of sheet metal and the groove is formed by crimping the metal, a rib 32 being pushed out on the opposite side of the sheet at the operation producing the groove. The snap fastener member may be of any suitable type or may be either male or female. Herein a female member of the type having a spring ring 33 is shown. In any type or variety the cupped portion is left open.

In Figure 3 are shown the burrs or jagged edges of metal formed when the staple pierces the fastener member. These burrs if left are likely to obstruct the proper mating of the snap fastener parts, would catch and retain dirt, grease or other material rendering the article unsanitary, would possibly injure the fingers of the user, and would be so unsightly as to create an unfavorable impression.

Herein I have shown a setting pin or die 40 for turning both the prongs of the staples and the burrs which they form in the fastener members. This setting pin must be of relatively small diameter for it must enter the open cupped portion of the fastener members to reach the staples. Heretofore so far as I am aware no setting die has been produced or designed capable of entering this limited opening and at the same time turning the burrs about the staple shanks.

This pin has a pair of grooves 41 sloping toward the center of their length and also sloping toward a partition wall 42. The grooves are sufficiently long and deep as shown in Figure 1 to accommodate all of the bent portion of the staple shanks. The edges of the grooves are thus allowed to reach the burrs to turn them. To assist in turning the burrs, the outer edge of the pin is flattened as shown at 43 in Fig. 5. The grooves 41 also are made somewhat wider at the center than is required for the diameter of the staple shanks and the inwardly sloping portions of the grooves at these

points serve to prevent the burrs bending outward as the flattened faces 43 come into action.

While one embodiment of the invention has been described with particularity, it will be apparent that changes may be made within the spirit of the invention as set forth in the appended claims.

I claim as my invention:

1. A fastener assembly comprising a fastener member, and a headed attaching member piercing a piece of goods and said fastener member and deformed behind the fastener member to secure the same on the goods, said attaching member including a pointed shank portion, a head and a cover affixed to said head, said cover including a sheet of material crimped intermediate its rim and center to form a socket for the head of said attaching member, a rib turned beneath said head and a lateral flange at the rim of the sheet, and a second sheet of material having a relatively smooth surface secured upon said crimped sheet and immediately overlying the socket portion of said crimped sheet and the head therebeneath, the head and cover thus assembled being sufficiently firm to resist crushing when the shank of the attaching member is driven to perform its piercing function.

2. A fastener attaching member comprising an element including a deformable shank and head and a cover for said head including a sheet of material crimped intermediate its rim and center to form an annular rib turned inward beneath said head, and a lateral flange at the rim, and a second sheet of material secured upon said crimped sheet and closely overlying the same above said head to form a smooth neat and substantial structure not easily bent by driving upon the head.

3. A fastener attaching member comprising a rivet having a piercing pointed shank and head and a cover for said head having sufficient strength and rigidity to force the rivet through sheet metal material without crushing the cover, said cover including a sheet of metal crimped between its rim and center to form a rib bent beneath said head to secure the cover thereon, the rim of said sheet and the lower surface of said rib after bending lying substantially in the same plane and said rivet deformed when in its attached position.

4. The device set forth in claim 3 which further includes in combination a second and relatively smooth sheet of metal attached to said crimped sheet so as to closely overlie the same to provide a smooth solid cover.

5. An attaching member for fasteners comprising a headed piercing member, a cap comprising a disk having a central chamber formed therein and the lower edges of the

walls of the chamber crimped under the head of the piercing member, said cap also comprising a crown and having its periphery crimped about the periphery of the disk.

5 6. An attaching member for fasteners comprising a riveting member, said riveting member comprising a headed staple, a cap comprising a disk having a chamber, the lower walls of which are crimped beneath the head of the staple to tightly hold the same, and a crown for the disk having its peripheral edge crimped about the peripheral edge of the disk.

15 7. A cap disc for headed devices formed from a sheet of metal comprising a downwardly extending peripheral rim portion, inwardly sloping side walls, upwardly positioned center walls and an integral cover, and said cap disc when in its final position 20 having the merging portion of the inwardly sloping side walls and the upwardly positioned center walls extending inwardly to form a locking flange.

25 8. A cap disk adapted to enclose the head of a piercing member, said cap disk comprising a peripheral downwardly extending rim portion, an inwardly extending sloping side wall connected therewith, a central vertical wall merging with the lower edge of 30 said inwardly extending side wall, and the sloping wall and the vertical wall, where they merge, being bent inwardly to form a flat rim to underlie the head of the piercing member.

35 9. A cap disc adapted to tightly grip a head of a staple, said disc being formed into a small hollow chamber with inwardly projecting lower walls, said walls then extending outwardly, upwardly and downwardly, and a cover crimped about the outer edges of said cap disc.

In testimony whereof, I have signed my name to this specification this 14th day of January, 1929.

45 LEONARD R. CARLEY.
